[57] CLAIM

The ornamental design for an engine exhaust emission analyzer, as shown and described.

DESCRIPTION

FIG. 1 is a left front perspective view of an engine analyzer showing our new design;
 FIG. 2 is a right rear perspective view thereof;
 FIG. 3 is a front elevational view thereof;
 FIG. 4 is a top plan view thereof;
 FIG. 5 is a right side elevational view thereof;
 FIG. 6 is a rear elevational view thereof;
 FIG. 7 is a bottom plan view thereof.
